STEAM GENERATOR

John Phillips Badenhausen, Philadelphia, Pa., assignor of one-half to Day and Zimmermann, Incorporated, Philadelphia, Pa., a corporation of Maryland

Application June 16, 1939, Serial No. 279,475

14 Claims. (Cl. 122—347)

This invention relates to steam generators and more particularly to a type of steam generator which is simple in construction and which is adaptable for the burning of combustible fuels of various kinds.

It is a further object of the present invention to provide a steam generator which will have a rapid circulation and which will be efficient in its steam generating action.

10 It is a further object of the present invention to provide a steam generator which may be operated at a high efficiency over a wide range of loads.

It is a further object of the present invention 5 to provide a steam generator which includes an integral economizer section for obtaining improved steam generation.

It is a further object of the present invention to provide a steam generator in which the quantity 20 of water for steam generation is relatively small so that variation in the water level with change of pressure is reduced to a minimum.

It is a further object of the present invention to provide an improved low head type of steam 25 generating unit.

Other objects of the present invention will be apparent from the annexed specification and claims.

The nature and characteristic features of the 30 invention will be more readily understood from the following description taken in connection with the accompanying drawings forming part hereof, in which:

Figure 1 is a vertical central sectional view 35 taken from front to rear of a preferred embodiment of the present invention;

Fig. 2 is a horizontal sectional view taken approximately on the line 2—2 of Fig. 1;

Fig. 3 is a vertical sectional view taken approximately on the line 3—3 of Fig. 1; and

Fig. 4 is a vertical sectional view similar to Fig. 3 and illustrative of a modified form of the invention.

It will, of course, be understood that the 45 description and drawings herein contained are illustrative merely, and that various modifications and changes may be made in the structure disclosed without departing from the spirit of the invention.

50 Referring more particularly to Figs. 1, 2 and 3 of the drawings in which a preferred embodiment of the steam generator of the present invention is illustrated, a front wall 10 is provided which has, preferably about midway between the top and bottom thereof, a suitable aperture 11 in

which the burner nozzle (not shown) for pulverized coal, oil, or other suitable fuel material is mounted. Side walls 12 and 13 are provided which extend upwardly from a floor 14, and inclined upper side wall sections 15 preferably connect the upper portions of the side walls 12 and 13 with generally horizontally disposed top wall portions 16. The top wall portions 16 are preferably connected by a curved top wall portion 17.

5 An upper steam and water drum 18 is provided 10 and is disposed at right angles to the front wall 10, generally parallel to the side walls 12 and 13 and preferably extends forwardly to and beyond the front wall 10 upon which it rests at the front.

An upwardly extending rear baffle member 20 is provided near the rear end of the steam and water drum 18 and extends from the floor 14 to a location adjacent but spaced from the steam and water drum 18 and from the upper wall portions 15 and the top wall portions 16 and 17. The space in front of the baffle member 20 is the main combustion space of the steam generator. To the rear of the baffle 20 a downwardly extending baffle 21 is provided which extends from the steam and water drum 18 and from the upper wall portions 15 and the top wall portions 16 downwardly toward the floor 14, the baffle 21 being spaced from the floor 14 to permit the passage of gas around the end thereof. A downward pass is 30 thus provided between the baffle 20 and the baffle 21.

An upwardly extending baffle 22 is also provided, the baffle 22 extending upwardly from the floor 14 and preferably being spaced at the top 35 thereof from the steam and water drum 18, the upper wall portions 15, and the top wall portions 16 to provide a space around which the gases may pass, as hereinafter referred to. An upward pass 40 is thus provided between the baffle 21 and the baffle 22.

At the rear end of the top wall portions 16, the upper wall portions 15 and the side walls 12 and 13, a downwardly extending baffle or rear wall 45 24 is provided. This baffle 24 extends toward but is spaced from the floor 14 for purposes herein-after more fully referred to and provides with the baffle 22 a downward pass. The steam and water drum 18 preferably terminates short of the rear baffle member 24.

A lower header 25 is provided intermediate the side walls 12 and 13 and is preferably horizontally disposed below the steam and water drum 18 and extends parallel thereto. A plurality of banks of steam generating tubes connect the header 25 55

with the steam and water drum 18, as hereinafter more fully pointed out.

5 A bank of downcomer tubes 26 is preferably provided outside the front wall 10 of the steam generator for connecting the steam and water drum 18 with the header 25.

10 Banks of riser tubes 27 and 28 are provided on each side, respectively, of the steam generator, the tubes of these banks preferably extending from the header 25 upwardly and outwardly to the side walls 12 and 13, respectively, then upwardly along the side walls 12 and 13, and inwardly along the inclined upper wall portions 15 and the top wall portions 16 to the steam and water drum 18. The tubes of the banks of tubes 15 27 and 28 are preferably staggered at their place of connection to the header 25 and to the drum 18 so that the tubes may be closely disposed without sacrifice of strength at the place of connection.

20 A bank of tubes 29 is also preferably provided on the inside of the front wall 10 and the tubes thereof preferably extend from the header 25 outwardly and then upwardly along the front wall 10 and then to the steam and water drum 18.

25 The upwardly extending baffle member 20 which forms the rear of the combustion space is preferably provided with a bank of tubes 30 along the front side thereof, and another bank of tubes 31 is provided along the rear side thereof, the tubes of these banks 30 and 31 preferably being partially embedded within the baffle 20 and assisting in the support of the baffle 20.

30 In the pass provided between the upwardly extending baffle 20 and the downwardly extending baffle 21, banks of tubes 34 and 35, substantially similar to the banks 27 and 28 for lining the side walls 12 and 13 thereof are preferably provided.

35 A bank of tubes 36 is also preferably provided along the baffle member 21; and the space or pass between the upwardly extending baffle member 20 and the downwardly extending baffle member 21 and the side walls 12 and 13 preferably has spaced tubes 33 therein extending from the lower header 45 25 to the upper steam and water drum 18.

40 In the pass between the downwardly extending baffle member 21 and the upwardly extending baffle member 22 a superheater is preferably provided. The superheater may be of any preferred type and may be connected to the steam and water drum in any desired manner, but in the form shown preferably includes a pair of headers 38 and 39. The header 38 is preferably connected to the steam and water drum 18 by a pipe 37 which in turn is connected to a collector tube 37^a having a plurality of slots or saw cuts 37^b for admitting steam thereto. Suitable banks of substantially horizontally disposed superheater tubes 40 extend 45 between the headers 38 and 39 and are disposed across the space toward the side wall 13. The superheater headers 38 and 39 are preferably vertically disposed in the side wall 12 of the steam generator.

50 In the space or pass between the upwardly extending baffle member 22 and the rearmost downwardly extending baffle member 24 an economizer section of the steam generator is preferably provided. The economizer may be of any preferred type, but in the form shown spaced economizer headers 42 and 43 are vertically disposed in the side wall 12 with banks of economizer tubes 44 connected therebetween.

55 The economizer section is preferably constructed in accordance with the disclosure of the prior ap-

lication of J. H. Rohrer, filed March 8, 1939, Serial No. 260,532.

60 The uppermost tubes 45 of the economizer section are preferably connected to the rear end portion of the steam and water drum 18 at a location 5 to the rear of the rear baffle member 20.

65 An air preheater 46 is also preferably provided, the upper end of which may be connected by the duct 47 to a suitable source of draft. The air preheater 46 preferably has air supplied to the air inlet 48 by a forced draft fan shown at 49 and the air preheated in the air preheater 46 is supplied from the air outlet 50 by means of a duct 51 and a duct 52 to a suitable front wall duct 53 from which it is delivered at the fuel inlet aperture 11. 15

70 A pair of inclined walls 55 are provided which extend from the floor 14 to the lower header 25 for supporting the same. The spaces between the banks of tubes 27 and 28 will permit the discharge of ash at the lower portions of these banks, if 20 pulverized coal or other ash bearing fuel is burned downwardly between the tubes and into the spaces above the bottom floor 14.

75 Clean-out doors 56 are preferably provided at the lower part of the combustion space and preferably in the front wall 10 for removing ash deposited on the floor 14. A clean-out door 57 is also preferably provided in the side wall 13 for removing any ash which is carried over from the combustion chamber, and a clean-out door 58 30 is also preferably provided in the side wall 13 for removing any ash carried over beyond the economizer section.

80 In the modified form of the invention as illustrated in Fig. 4, in place of the single lower header 25 as illustrated in Fig. 3, two lower headers 25^a are provided adjacent the lower part of the side walls 12 and 13. The headers 25^a may have a grate or stoker, illustrated diagrammatically at 59, extending therebetween. 10

85 The banks of tubes extending between the headers 25^a and the steam and water drum 18 are substantially the same as the banks of tubes illustrated in the form of the invention previously described, but are distributed between the two 45 headers 25^a.

90 In the form of the invention as illustrated in Fig. 4, the bank tubes 27^a on one side of the center connect the header 25^a along the side wall 12 to the steam and water drum 18, and the bank of 50 tubes 28^a on the other side of the center connect the header 25^a along the side wall 12 to the steam and water drum 18. Similarly, also, the tubes 30^a in front of the baffle 20 on one side extend from the lower header 25^a along the wall 12, and on the 55 other side extend from the lower header 25^a along the wall 13 to the steam and water drum 18.

95 The tubes 33^a in the pass immediately to the rear of the baffle 20 are also connected respectively from the headers 25^a to the steam and 60 water drum 18.

100 The mode of operation of the steam generator of the present invention will be apparent from the foregoing. It may be pointed out, however, that the major portion of the combustion of the combustible materials introduced at the burner (not shown) in the burner aperture occurs in the combustion space between the front wall 10 and the baffle 20. The banks of tubes 27 and 28 along the side walls 12 and 13 and extending to the steam and water drum 19 furnish a large surface for rapid and effective steam generation. Any ash which is present with the fuel will fall to the bottom of the combustion space and between the spaces provided between the tubes of the banks 75

of tubes 27 and 28. The hot gases will move from the upper rear portion of the combustion space downwardly in the pass between the baffle 20 and the baffle 21 and the gases will sweep over and along the tubes of the banks of tubes 31, 33, 34 and 36. The hot gases will then pass upwardly in the pass between the baffle 21 and the baffle 22 and in contact with the superheater tubes 40 for superheating the steam therein by convection. The combustion gases will then pass around the upper end of the baffle 22 and downwardly in the pass provided between the baffle 22 and the baffle 24 and in contact with the tubes 44 of the economizer section where a further portion of the heat will be given up. The combustion gases will then pass upwardly through the air heater 46 for preheating the air for combustion supplied by the forced draft fan 49 through the air inlet 48, and the combustion gases will then be drawn off or pass off to the stack (not shown) through the duct 47.

I claim:

1. In a steam generator, a front wall having a fuel inlet opening, spaced side walls, an upper steam and water drum extending from front to rear and parallel to said side walls, a horizontal lower water header arranged intermediate the side walls at the lower part thereof and vertically below said steam and water drum, tubes extending between said header and said steam and water drum along said front wall, riser tubes extending from the lower header to the steam and water drum and lining the side walls, a baffle adjacent the rear end of the steam and water drum and providing the rear boundary of the combustion space, additional baffles adjacent the rear end of said steam and water drum and to the rear of said first mentioned baffle, banks of tubes extending between said header and said steam and water drum in the spaces between said additional baffles.

2. In a steam generator, a front wall having a fuel inlet opening, spaced side walls, an upper steam and water drum extending from the front wall and parallel to the side walls, a lower water header arranged intermediate the side walls at the lower part thereof and vertically below the steam and water drum, tubes extending between said header and said steam and water drum along said front wall, riser tubes extending from the lower header to the steam and water drum and lining the side walls, an upwardly extending baffle adjacent the rear end of the steam and water drum and providing the rear boundary of the combustion space, baffles to the rear of said first mentioned baffle providing a plurality of passes, and additional steam generating tubes extending to said steam and water drum in the spaces between said baffles.

3. In a steam generator, a front wall having a fuel inlet opening, spaced side walls, an upper steam and water drum extending from front to rear and parallel to said side walls, a lower water header disposed substantially parallel to the steam and water drum, tubes extending between said header and said steam and water drum along said front wall, closely spaced tubes lining the side walls and extending to said steam and water drum, said tubes being connected to said steam and water drum in staggered relationship, an upwardly extending baffle adjacent the rear end of the steam and water drum and providing the rear boundary of the combustion space, steam generating tubes extending to said steam and water drum and along each face of said baffle, additional baffles to the rear of said first mentioned baffle,

and steam generating tubes in the spaces between said baffles and connected to said steam and water drum.

4. In a steam generator, a front wall having a fuel inlet opening, spaced side walls, a top wall portion, an upper steam and water drum in said top wall portion, an upper steam and water drum in said top wall portion extending from the front wall generally parallel to the side walls, a lower water header arranged intermediate the side walls at the lower part thereof and substantially parallel to the steam and water drum, tubes extending between said header and said steam and water drum along the inner side of the front wall, steam generating tubes extending from the lower header to the steam and water drum and lining the side walls, said tubes being spaced to permit ash to fall therebetween at the lower portions of the tubes and an upwardly extending baffle adjacent the rear end of the steam and water drum and providing the rear wall of the combustion space. 20

5. In a steam generator, a front wall having a fuel inlet opening, spaced side walls, a top wall portion, an upper steam and water drum in said top wall portion, an upper steam and water drum in said top wall portion extending from the front wall generally parallel to the side walls, a lower water header arranged intermediate the side walls at the lower part thereof and substantially parallel to the steam and water drum, tubes extending between said header and said steam and water drum along the inner side of the front wall, steam 30 generating tubes extending from the lower header to the steam and water drum and lining the side walls, said tubes being spaced and being connected to said header in staggered relationship and a baffle adjacent the rear end of the steam and 35 water drum and providing the rear wall of the combustion space, and banks of tubes along said baffle and extending from said header to said steam and water drum.

6. In a steam generator, a front wall having a fuel inlet opening, side walls, a top wall portion, an upper steam and water drum in said top wall portion extending from the front wall generally parallel to the side walls, a lower water header arranged intermediate the side walls at the lower 45 part thereof and substantially parallel to the steam and water drum, tubes extending between said header and said steam and water drum along the inner side of the front wall, steam generating tubes extending from the lower header to the 50 steam and water drum and lining the side walls, said tubes being spaced at the lower portions thereof, a baffle adjacent the rear end of the steam and water drum and providing the rear wall of the combustion space, a baffle adjacent the rear 55 end of said steam and water drum and to the rear of said first mentioned baffle, and tubes extending from said header to said steam and water drum in the space between said baffles.

7. In a steam generator, a front wall having a fuel inlet opening, side walls, a top wall portion, an upper steam and water drum in said top wall portion, an upper steam and water drum in said top wall portion extending generally parallel to the side walls, a lower water header arranged intermediate the side walls at the lower part thereof and substantially parallel to the steam and water drum, tubes extending between said header and said steam and water drum along the inner side of the front wall, steam generating tubes extending from the lower header to the steam and water drum 70 and lining the side walls, said tubes being spaced at the lower portions thereof and connected to said header in staggered relationship, a baffle adjacent the rear end of the steam and water drum and providing the rear wall of the combustion 75

space, a baffle adjacent the rear end of said steam and water drum and to the rear of said first mentioned baffle, tubes extending from said header to said steam and water drum in the space between said baffles, additional baffles to the rear of said other baffles providing an economizer space, and an economizer in said economizer space connected to said steam and water drum.

8. In a steam generator, a front wall having a fuel inlet opening, side walls, a top wall portion, an upper steam and water drum extending along said top wall portion from the front wall generally parallel to the side walls, a lower water header arranged intermediate the side walls at the lower part thereof and substantially parallel to the steam and water drum, tubes extending between said header and said steam and water drum along the inner side of the front wall, steam generating tubes extending from the lower header to the steam and water drum and lining the side walls, said tubes being connected to said drum and to said header in staggered relationship, an upwardly extending baffle adjacent the rear end of the steam and water drum and providing the rear wall of the combustion space, tubes extending to said steam and water drum along one side of said baffle, a downwardly extending baffle adjacent the rear end of said steam and water drum and to the rear of said first mentioned baffle, tubes extending from said header to said steam and water drum in the space between said baffles, additional baffles to the rear of said other baffles providing an economizer space, and an economizer in said economizer space consisting of a plurality of tubes connected at the top thereof to said steam and water drum.

9. In a steam generator, a front wall having a fuel inlet opening, side walls, a top wall portion, an upper steam and water drum extending along said top wall portion from the front wall generally parallel to the side walls, a lower water header arranged intermediate the side walls at the lower part thereof and substantially parallel to the steam and water drum, tubes extending between said header and said steam and water drum along the inner side of the front wall, steam generating tubes extending from the lower header to the steam and water drum and lining the side walls, said tubes being connected to said drum and to said header in staggered relationship, an upwardly extending baffle adjacent the rear end of the steam and water drum and providing the rear wall of the combustion space, tubes extending to said steam and water drum along each side of said baffle, a downwardly extending baffle adjacent the rear end of said steam and water drum and to the rear of said first mentioned baffle, tubes extending from said header to said steam and water drum in the space between said baffles, additional baffles to the rear of said other baffles providing an economizer space, and an economizer in said economizer space consisting of a plurality of substantially horizontal tubes extending from one of said side walls and connected at the top thereof to said steam and water drum.

10. In a steam generator, a front wall, side walls, a top wall portion, an upper steam and water drum along said top wall portion extending from the front wall generally parallel to the side walls, a pair of spaced lower water headers arranged horizontally along the side walls at the lower part thereof and substantially parallel to the steam and water drum, tubes extending between said headers and said steam and water

drum along the inner side of the front wall, steam generating tubes extending from each of said lower headers to the steam and water drum and respectively lining the side walls, an upwardly extending baffle adjacent the rear end of the steam and water drum and providing the rear wall of the combustion space, tubes extending from said lower water headers to said steam and water drum along each side of said baffle, a downwardly extending baffle adjacent the rear end of said steam and water drum and to the rear of said first mentioned baffle, tubes extending from said headers to said steam and water drum in the space between said baffles, additional baffles to the rear of said other baffles providing an economizer space, and an economizer in said economizer space consisting of a plurality of tubes connected at the top thereof to said steam and water drum.

11. In a steam generator, a front wall, spaced side walls, an upper steam and water drum extending from the front wall and parallel to the side walls, lower water header means extending rearwardly from said front wall below said steam and water drum and disposed substantially parallel to said drum, riser tubes extending from the header means to the steam and water drum and lining the side walls, a baffle adjacent the rear end of the steam and water drum and providing the rear boundary of the combustion space, steam generating tubes extending from said header means to said steam and water drum and along at least one face of said baffle, a baffle adjacent the rear end of said steam and water drum and to the rear of said first mentioned baffle, and spaced tubes extending from said header means to said steam and water drum and in the space between said baffles.

12. In a steam generator, a front wall, spaced side walls, an upper steam and water drum extending from the front wall and parallel to the side walls, lower water header means extending rearwardly from said front wall below said steam and water drum, and disposed substantially parallel to said steam and water drum, riser tubes extending from the header means to the steam and water drum and lining the side walls, a baffle adjacent the rear end of the steam and water drum and providing the rear boundary of the combustion space, steam generating tubes extending from said lower water header means to said steam and water drum and along each face of said baffle, a baffle adjacent the rear end of said steam and water drum and to the rear of said first mentioned baffle, spaced tubes extending from said header means to said steam and water drum and disposed in the space between said baffles, additional baffles to the rear of said other baffles providing an economizer space, and an economizer in said economizer space below and connected to said steam and water drum.

13. In a steam generator, a front wall, spaced side walls, a top wall portion, an upper steam and water drum in said top wall portion extending from the front wall and parallel to the side walls, lower water header means extending rearwardly from said front wall below said steam and water drum, said means comprising a pair of spaced headers arranged along the side walls at the lower part thereof and substantially parallel to the steam and water drum, riser tubes extending from said headers to the steam and water drum and lining the respective side walls, a baffle adjacent the rear end of the steam and

water drum and providing the rear boundary of the combustion space, steam generating tubes extending from said headers to said steam and water drum and disposed along at least one face of said baffle.

5 14. In a steam generator, a front wall, spaced side walls, a top wall portion, an upper steam and water drum in said top wall portion extending from the front wall and parallel to the side 10 walls, lower water header means extending rearwardly from said front wall below said steam and water drum, said header means comprising a pair of spaced headers arranged along the side walls at the lower part thereof and substantially 15 parallel to the steam and water drum, tubes extending between said headers and said steam and

water drum along the inner side of the front wall, steam generating tubes extending from each of said lower headers to the steam and water drum and respectively lining the side walls, an upwardly extending baffle adjacent the rear end 5 of the steam and water drum and providing the rear wall of the combustion space, steam generating tubes extending upwardly from said lower headers to said steam and water drum and along the faces of said baffle, a downwardly extending 10 baffle adjacent the rear end of said steam and water drum and to the rear of said first mentioned baffle, and spaced tubes extending from said headers to said steam and water drum and disposed in the space between said baffles.

15 JOHN PHILLIPS BADENHAUSEN.
